William B. Kochner, St. Louis, Mo., and Lawrence T. Ward, Newark, N. J., assignors to Knapp-Monarch Company, St. Louis, Mo., a corporation of Missouri

Application August 4, 1943, Serial No. 110,838

Term of patent 14 years

(Cl. D71—1)

To all whom it may concern:

Be it known that we, William B. Kochner and Lawrence T. Ward, citizens of the United States and residents of the city of St. Louis and State of Missouri, and of East Orange, in the county of Essex and State of New Jersey, respectively, have invented a new, original, and ornamental Design for a Combined Gauge and Safety Valve Unit for Rubber Boats or the like, of which the following is a specification, reference being had to the accompanying drawing, forming a part thereof.

Figure 1 is a front elevational view of a combined gauge and safety valve unit for rubber boats or the like embodying our new design.

Figure 2 is a bottom plan view of Figure 1.

Figure 3 is an end elevation of Figure 1.

We claim:

The ornamental design for a combined gauge and safety valve unit for rubber boats or the like, substantially as shown.

WILLIAM B. KOCHNER.
LAWRENCE T. WARD.
